(57) CLAIM

The ornamental design for a LED lamp body, as shown and described.

DESCRIPTION

FIG. 1 is a perspective view of an LED lamp body showing our new design.

FIG. 2 is a front elevational view thereof.

FIG. 3 is a rear elevational view thereof.

FIG. 4 is a left-side, elevational view thereof.

FIG. 5 is a right-side, elevational view thereof.

FIG. 6 is a top plan view thereof.

FIG. 7 is a bottom plan view thereof; and,

FIG. 8 is a view similar to FIG. 1, showing an LED, an envelope and a sleeve being mounted to the LED lamp body, wherein the LED, envelope and sleeve are shown in broken lines for illustrative purposes only and form no part of the claimed design.
